(57) CLAIM

The ornamental design for a golf club head, as shown and described.

DESCRIPTION

FIG. 1 is a toe end perspective view of a golf club head showing our new design;

FIG. 2 is a heel end perspective view thereof, and,

FIG. 3 is a bottom view thereof.

The broken lines immediately adjacent the shaded area form unclaimed boundaries of the design. The broken line showing of the remainder of the golf club head is for illustrative purposes only and forms no part of the claimed design.
